UNITED STATES PATENT OFFICE

129,631

DESIGN FOR A CONDIMENT SHAKER

William Henry Bowers, Rosemont, Pa., assignor to Victor Metal Products Corporation, Brooklyn, N. Y., a corporation of New York

Application June 5, 1941, Serial No. 101,308

Term of patent 7 years

To all whom it may concern:

Be it known that I, William Henry Bowers, a citizen of the United States and resident of Rosemont, in the county of Montgomery and State of Pennsylvania, have invented a new, original, and ornamental Design for a Condiment Shaker, of which the following is a specification, reference being had to the accompanying drawing, forming part thereof.

Fig. 1 is a top plan view of a condiment shaker showing my new design.

Fig. 2 is a front elevational view of the same.

The characteristic feature of my design resides in the condiment shaker disclosed having a spherical container or body portion with a flat circular base and said body portion meeting the convex neck or dispensing portion of the shaker in a horizontal circular line of intersection as shown.

I claim:

The ornamental design for a condiment shaker, substantially as shown and described.

WILLIAM HENRY BOWERS.
